UNITED STATES PATENT OFFICE.

EUGENE F. BEEBE, OF MINNEAPOLIS, MINNESOTA.

CLOTHES WRINGER.

Application filed February 5, 1920. Serial No. 356,477.

To all whom it may concern:

Be it known that I, EUGENE F. BEEBE, a citizen of the United States, resident of Minneapolis, county of Hennepin, State of Minnesota, have invented certain new and useful Improvements in Clothes Wringers, of which the following is a specification.

My invention relates to clothes wringers and particularly to a releasing device where-
10 by the pressure of the upper roll may be instantly released and the rolls allowed to separate in case the operator catches a finger or a portion of the hand between the rolls or it is desired to withdraw a garment
15 that may have been inserted between the rolls.

A further and particular object is to provide a releasing device which will be simple and positive in its action and while partic-
20 ularly adapted for a metal frame wringer may be used with wringers of any other type.

The invention consists generally in vari-
25 ous constructions and combinations, all as hereinafter described and particularly pointed out in the claims.

In the accompanying drawings forming part of this specification,

Figure 1 is a longitudinal vertical section
30 on the line 1—1 of Figure 2,

Figure 2 is a plan view of the wringer,

Figure 3 is a similar view, showing the parts in their released position,

Figure 4 is a sectional view on the line
35 4—4 of Figure 2,

Figure 5 is a sectional view on the line
5—5 of Figure 2,

Figure 6 is a sectional view on the line
6—6 of Figure 2,

Figure 7 is a sectional view showing the manner of mounting the wing nuts on the tension studs on the wringer.

Figure 8 is a detail view showing the means for connecting the sections of the
45 wing nuts.

In the drawing, 2 represents the frame of the wringer, having brackets 3 provided with clamping bolts 4 by means of which the wringer is mounted on the wall of a tub
50 in the usual way, as by means of a swing-
ing arm. The frame 2 is provided with up-

wardly projecting studs 5 having threaded upper ends and upon these studs I mount the arm 6 for the lower roll 7 and the arm 8 for the upper roll 9. Said arms have a 55 bearing 10, one upon the other, on the opposite side of the studs 5 from the rolls. Compression springs 11 are mounted on the studs 5 and seated at their lower ends on the arms 8 and when these springs are put 60 under compression the rolls will be forced together to squeeze the material between them and yieldingly resist separation. The shaft of the lower roll is provided with a gear 12 driven from a suitable source of 65 power and a sleeve 13 having a pin and slot connection 14 with the lower roll is mounted to slide toward and from the hub of the gear 12 and has a clutch connection 15 therewith. When this sleeve is withdrawn, 70 the lower roll is stationary and is driven when the sleeve is projected into engagement with the clutch in the hub of the gearing.

A plate 16 is provided, having holes 75 therein in which the threaded ends of the studs 5 are free to slide and cone-shaped walls 18 are formed on said plate around said holes to engage the correspondingly shaped surfaces 19 on the wing nut sections 20 and 20^a which are interiorly threaded to 80 engage the threads of the studs 5 so that when they are revolved on the studs to compress the springs, a downward pressure will be exerted on the rolls to increase the pressure on the garments between them. The 85 plate 16 is provided at each end with wings 21 and 22 pivoted at 23 on the plate 16 and having curved inner faces 24 adapted to encircle the sections of the wing nuts and hold them in interlocking engagement with 90 the threads of the studs.

The wings 21 and 22 are preferably pro-
vided with lugs 25 adapted to enter notches
26 provided in sliding bars 27 and 27^a mounted upon the plate 16 and having a 95 longitudinal movement with respect thereto by means of the slots 28 and pins 29. The middle portion of the plate 16 has a hub 30 thereon provided with a central pivot pin 31 on which a lever 32 is mounted and 100 is yieldingly held in engagement with the hub by a spring 33. The bars 27 and 27^a

have curved end portions to receive the hub 30 and extensions 34 and 35 which are connected with the lever 32 on the opposite sides of its center by pivot pins 36. This lever is 5 provided with a finger grip 37. When it is moved to the position shown in Figure 2, the bars 27 and 27^a through the cam action of the lever will be projected to engage and lock the wings 21 and 22 and when this is 10 done, the wing nuts will be held against separation and may be screwed down on the studs until the desired degree of pressure is obtained on the lower roll. Should occasion 15 arise when instantaneous release of this pressure is desired, the operator has only to strike the finger grip 37 and move the lever to the position shown in Figure 3, when the bars 27 and 27^a will be retracted, releasing 20 the wings and allowing the wing nuts to become automatically separated from the threads of the studs. I prefer to connect 25 the sections of the wing nuts by a link 38 which will hold them together when released from engagement with the threads of the studs.

For the purpose of checking the movement of the lower roll, I prefer to provide the bar 27 with a downwardly projecting extension 39 having a fork 40 to engage the 30 clutch sleeve 13 and move it back and forth on the shaft 41 of the driving gear 12 to lock or release the lower roll. When the bars are returned to their locking position, the clutch sleeve will also be moved to lock 35 the lower roll.

I claim as my invention:

1. A clothes wringer comprising a frame, upper and lower rolls, studs mounted in said frame, springs mounted on said studs and 40 exerting a downward pressure on the upper roll, a plate slidable on said studs, split wing nuts having threaded engagement with said studs, means for locking said wing nuts in engagement with the threads of said studs, 45 and a lever mechanism for simultaneously releasing said wings and allowing said nuts to separate.

2. A clothes wringer comprising a frame, upper and lower rolls, threaded studs 50 mounted in said frame, springs carried by said studs, a plate movable on said studs and seated on said springs, wing nut sections to engage said studs and hold said plate against the tension of said springs, 55 means engaging said wing nut sections for holding them in their closed position, and a lever operated device for releasing said last named holding means.

3. A clothes wringer comprising a frame, 60 rolls therefor, one of said rolls having a driving means and a clutch control therefor, studs mounted in said frame, springs carried by said studs, a plate movable on said studs and seated on said springs, bars

mounted to slide on said plate, one of said bars having a depending end to engage said clutch control, means for holding said plate on said studs, and means for reciprocating said bars to release said holding means and simultaneously operate said clutch. 65 70

4. A clothes wringer comprising a frame, upper and lower rolls, studs mounted in said frame, springs carried by said studs, a plate mounted on said studs and normally held in a raised position by said springs, bars 75 mounted to slide on said plate, a lever for reciprocating said bars, means for holding said plate and bars against vertical movement, the disengagement of said bars from said holding means allowing said plate to 80 move automatically under the tension of said springs to its release position.

5. A clothes wringer comprising a frame, rolls therefor, one of said rolls having a driving means and a clutch control therefor, 85 studs mounted in said frame, springs carried by said studs, a plate movable on said studs and seated on said springs, bars mounted to slide on said plate, means for locking said plate on said studs, said locking means being released by the movement of said bars, and means actuated by the movement of one of said bars to its release position for moving said clutch control to its release position. 90 95

6. A clothes wringer comprising a frame, rolls therefor, one of said rolls having a driving means and a clutch control therefor, means for locking said rolls in their 100 normal working position, reciprocating bars mounted to trip said locking means and release said rolls, one of said bars having a depending portion for engaging and operating said clutch control simultaneously with the release of said locking means. 105

7. A clothes wringer comprising a frame, upper and lower rolls, threaded studs mounted in said frame, springs carried by 110 said studs, a plate movable on said studs and normally held in its raised position by said springs, sectional wing nuts mounted to engage said studs and hold said plate against the tension of said springs, means mounted to clamp the sections of said wing nuts and hold them against separation, and means for releasing said wing nut section holding means. 115

8. In a clothes wringer, the combination of a supporting frame, a wringer roll and its tensioning springs, means for holding 120 said springs in operative position, said means including a plurality of split nuts, individual means for normally holding each of said split nuts in operative position, and a single member for releasing all of said 125 means.

9. In a clothes wringer, the combination of a frame, a wringer roll and its springs,

threaded rods co-operating with said springs, a split nut adapted to secure each of said rods, and means common to said nuts for locking and releasing them.

5 10. In a clothes wringer, the combination of a frame, a wringer roll and its springs, threaded rods for regulating the compres-

sion of said springs, split nuts adapted to secure said rods, and means projectable and withdrawable for respectively locking and 10 releasing said split nuts simultaneously.

In witness whereof, I have hereunto set my hand this 31st day of January, 1920.

EUGENE F. BEEBE.
